UNITED STATES PATENT OFFICE.

CHARLES RICHTMANN, OF NEWARK, NEW JERSEY, ASSIGNOR, BY MESNE ASSIGNMENTS, TO RICHARD R. WATSON, OF NEW YORK, N. Y.

WEIGHING-SCALE.

SPECIFICATION forming part of Letters Patent No. 312,583, dated February 17, 1885.

Application filed April 11, 1884. (No model.)

To all whom it may concern:

Be it known that I, CHARLES RICHTMANN, of Newark, in the county of Essex and State of New Jersey, have invented certain new and 5 useful Improvements in Weighing-Scales, of which the following is a specification.

This invention has reference to certain improvements in weighing-scales, and especially in scales for weighing letters and packages; 10 and the invention consists of a weighing-scale the beam of which is made of a hollow U-shaped main piece, solid end pieces, and a graduated scale-plate at the top of the beam. The weight, sliding on the beam, is provided 15 with a projecting tongue and spring-lip that takes into the depressed middle portions of the graduations of the scale-plate. The scale-pan is suspended on knife-edges of the beam by a U-shaped link provided with a stop, to 20 prevent the detaching of the pan. The pan is provided with an elastic cushion at the under side and with a central depression or cup for the reception of the adjusting-shot, which is retained by a covering-plate secured by bent 25 ends over the edges of the pan.

In the accompanying drawings, Figure 1 represents a side elevation, and Fig. 2 a plan, of my improved weighing-scale. Fig. 2^a is a detail side view of the fulcrumed front piece 30 of the scale-beam. Fig. 3 is an end elevation, partly in section, of my improved weighing-scale. Figs. 4 and 5 are respectively a vertical transverse section and a vertical longitudinal section of the sliding weight on lines 35 x x and y y, Fig. 2; and Fig. 6 is a detail section of the suspension-link of the scale-pan.

Similar letters of reference indicate corresponding parts.

A in the drawings represents the supporting 40 post or standard of my improved weighing-scale, the base of which is provided with a forward-extending heel, a, by which the tilting of the scale is prevented. The post A is provided with a horizontal bracket, B, that 45 extends in opposite direction from the post A, and is provided at one end with a forked vertical support, B', for the knife-edged fulcra of the scale-beam C, and at the opposite end with a vertical guide staple or loop, B², for 50 the rear end of the scale-beam C. The scale-beam C is made of a hollow main piece of

U-shaped cross-section, which is bent up or drawn out of suitable metal. On the outwardly-bent flanges of the U-shaped main piece is supported a graduated scale-plate, C', 55 which is soldered, riveted, or otherwise secured to the U-shaped beam C. The ends d d' of the scale-beam C are made of solid metal, the fulcrumed front piece, d, being provided with a shoulder, d², at the upper part, against 60 which abuts the end of the scale-plate, and with a second shoulder, d³, at the lower part, against which abuts the end of the hollow main piece of the scale-beam, as shown clearly in Figs. 1 and 2^a. As the end of the scale-plate C' extends over the front piece, d, and beyond the point of connection of the beam with the same, a more rigid connection of 65 these parts is obtained. The rear end, d', is inserted and soldered into the rear end of the 70 beam C.

The advantage of the hollow scale-beam C, having a scale-plate, C', at the top, is that thereby the weight of the scale-pan and of the sliding counterpoise can be considerably decreased; and, secondly, that by the arrangement of the scale at the top of the beam the weight of the articles placed in the scale-pan can be read off with great facility without stooping down and reading it off at the side 80 of the scale-beam, as heretofore. A counter-weight, C², of U shape, slides on the beam C. It is retained thereon by inwardly-projecting stop-screws b b, which take below the flanged edges of the beam. A tongue, b', made of a 85 spring-plate that is riveted to the inside of the weight C², is retained by laterally-projecting stops or shoulders b² (shown in Fig. 2) on the weight C², and provided at a suitable point within the weight C² with a downwardly-bent 90 lip, b³, that is integral with the body of the tongue b', and adapted to engage the depressed middle portions of the graduations of the scale-plate C', as shown clearly in Fig. 5. The lip b³ "gives" sufficiently to clear the depressions of the beam when the weight C² is moved in either direction over the beam. The figures indicating the graduations are preferably arranged at both sides of the middle depressed portions. The weight C² on being 95 moved over the beam C is readily retained by the lip b³ at any one of the graduations of 100

the scale-plate, so as to facilitate thereby the quick adjustment of the weight in weighing a letter, package, or other article.

- To knife-edges of the front piece, d , of the beam C, is hung a scale-pan, D, by a suspension-link, D^2 , and bent wire arms $D'D'$. The arms D' are riveted to the link D^2 , that rests on the knife-edges at the end of the beam C, said link being made of cast metal, and provided with an upwardly-projecting stop, D^3 , that is screwed to the middle portion or web of the suspension-link D^2 . The lower ends of the arms D' are attached to perforated ears e of the pan D. The middle portion of the scale-pan D is provided with a depression or cup, f , and the latter with a central downwardly-extending stud, f' , cast integral therewith. The depression or cup f receives the shot by which the proper balancing of the scale-pan and beam is adjusted. The stud f' is covered with an exterior sleeve or socket, f^2 , of rubber or other elastic material, which acts as a cushion when the scale-pan strikes the table or other support.
- To retain the shot in the cup f , a sheet-metal top plate, D^4 , is extended over the upper surface of the pan D, between the end flanges of the same, and attached by its bent edges thereto.
- The advantages of my improved weighing-scale are, first, that by the light construction of the scale-beam the weight of the parts and the expense are decreased; second, that the weight of the letters and packages placed in the scale-pan can be quickly and economically read off on the top scale-plate of the beam; and, third, that by the rubber cushion of the scale-pan the oscillations of the scale-beam are made shorter, so that the proper balance of the counterpoise on the beam and of the articles placed is obtained in a quicker manner.

Having thus described my invention, I claim as new and desire to secure by Letters Patent—

1. In a weighing-scale, a scale-beam composed of a hollow main piece of U-shaped cross-section and of a scale-plate secured to the top of the same, substantially as set forth.
2. A scale-beam composed of a hollow U-

shaped main piece, a scale-plate secured to the top of the same, and end pieces secured to the ends of the beam, substantially as described.

3. The combination of a hollow U-shaped main piece, C, top scale-plate, C', rear piece, d' , and front end piece, d , having a top shoulder, d^2 , and a bottom shoulder, d^3 , substantially as set forth.

4. The combination of a fulcrumed scale-beam made of a hollow U-shaped main piece and of a scale-plate secured to the top of the same, with a sliding weight, C², having inwardly-projecting stops b and an index-tongue, b' , substantially as specified.

5. The combination of a fulcrumed scale-beam composed of a hollow U-shaped main piece and of a graduated scale-plate, the graduations of said scale-plate having depressed middle portions, with a sliding weight, C², having stops b and an index-tongue, b' , with a downwardly-projecting lip, b^3 , that takes into the depressions of the scale-plate, substantially as set forth.

6. The combination, with a scale-beam having a scale-plate at the top, of a sliding weight, C², having guide-stops b and an index-tongue, b' , said index-tongue having laterally-projecting end shoulders, b^2 , and a bent lip, b^3 , substantially as specified.

7. The combination of the fulcrumed scale-beam C, having knife-edges at its front end, with a suspension-link, D', a scale-pan, D, secured thereto by arms D², and a stop, D³, whereby the detaching of the suspension-link from the beam is prevented, substantially as set forth.

8. A scale-pan having a central depression or cup, f , a downwardly-extending button-stud, f' , and an elastic covering-socket, f^2 , that acts as a cushion for the pan, substantially as set forth.

In testimony that I claim the foregoing as my invention I have signed my name in presence of two subscribing witnesses.

CHARLES RICHTMANN.
